UNITED STATES PATENT OFFICE.

SANJIRO MATSUSAKI, OF VANCOUVER, BRITISH COLUMBIA, CANADA.

HANDBAG.

1,362,884.

Specification of Letters Patent. Patented Dec. 21, 1920.

Application filed December 13, 1919. Serial No. 344,587.

To all whom it may concern:

Be it known that I, SANJIRO MATSUSAKI, a subject of the Emperor of Japan, and a resident of the city of Vancouver, in the 5 Province of British Columbia, Canada, have invented certain new and useful Improvements in Handbags, of which the following is a specification.

My invention relates to improvements in 10 handbags, and the object of my invention is to devise a bag of this character the capacity of which may be restricted at will so that it may be rendered very convenient and neat appearing when the full capacity of 15 the bag is not required and which may also be folded up into small bulk for carrying in a pocket or other receptacle if desired.

I attain this object by the construction 20 illustrated in the accompanying drawings in which—

Figure 1 is a view of the bag opened to full size.

Fig. 2 is a view of the bag restricted to 25 reduce its capacity.

Fig. 3 is a view showing how the bag may be folded.

Similar figures of reference indicate similar parts throughout the several views.

The bag consists of two upper end bars, 30 indicated generally by the numerals 1 and 2, flexibly connected together at their opposite ends, from which bars depends the mesh 3 which forms the bag or receptacle proper. This receptacle, may, however, be 35 made of any suitable material. Threaded through the mesh at the lower end of the bag is a draw string 4, from which it will be readily seen that the lower end of the bag may be drawn together, as shown in Fig. 2 40 reducing its capacity considerably, and, after knotting the draw string, may be used to carry smaller parcels while at the same time presenting a very neat appearance.

The bars 1 and 2 are provided with suitable handles 5 and 6, and while these bars 45 may be each made in one piece it is preferable to make them in two pieces, 7—8 and 9—10 respectively, and flexibly connect these pieces together so that should it be desired to fold the bag into small bulk all that is 50 necessary is to fold the pieces 7—9 on to the pieces 8—10 and then wrap the mesh work around the bars and the handles, thus forming a small compact parcel which may be readily carried in the pocket. When it is 55 desired to use the bag the bars are straightened out, bringing the bag back again into the form shown in either Fig. 1 or Fig. 2. The handles 5 and 6 are flexibly connected to the bars by rings 11 and the length of 60 the connection is such as will permit of the folding of the bars as described.

From the foregoing it will be seen that I have devised a simple, inexpensive, convenient and neat handbag.

What I claim as my invention is:—

A hand bag comprising a frame including a pair of normally parallel side members each comprising a pair of bars disposed end to end in the same vertical plane and having 70 the inner ends thereof flexibly connected together and the outer ends thereof flexibly connected to the corresponding ends of the opposing pair of bars, the arrangement being such as to permit the opposing bars at 75 one end of the frame to be folded to lie flatly against the opposing bars at the opposite end of the frame, and a hand bag having the mouth portion thereof attached to said bars.
